UNITED STATES PATENT OFFICE.

ALFRED H. MEECH, OF CHATHAM, NEW YORK, ASSIGNOR TO ELEVATOR AIR BRAKE COMPANY, A CORPORATION OF MISSOURI.

ELEVATOR-BRAKE.

1,206,350.

Specification of Letters Patent. Patented Nov. 28, 1916.

Application filed July 12, 1910. Serial No. 571,576.

To all whom it may concern:

Be it known that I, ALFRED H. MEECH, a citizen of the United States, residing at Chatham, in the county of Columbia and 5 State of New York, have invented certain new and useful Improvements in Elevator-Brakes, of which the following is a full, clear, and exact description.

This invention relates to elevator brakes 10 and has special reference to the mounting of the brake-shoes of such installations.

The invention is designed to be used with 15 elevator air-brakes of the type set forth in my prior Patents Nos. 722,736, 860,986 and 962,037, but is, however, applicable to all elevator brakes and similar installations where a car is guided slidably on rails.

An elevator ascending and descending in a shaft represents at times immense potential 20 and kinetic energy. For example, if the suspended cables of a heavily loaded car break when the car is at the top of a shaft, the car will descend with a steadily increasing kinetic energy, which may amount to 25 thousands of foot-pounds in a few seconds. Hence the importance of a brake of great certainty and holding power in case a brake is relied upon to arrest the descent of a car in the event of an accident. In my experiments I have evolved a brake having 30 adequate holding power and certainty of action to stop an elevator car even if very heavily loaded and sliding on greased and polished rails, and which will not abrade or 35 destroy the rails by numerous or even practically continuous applications.

The essential principle of the mechanism depends upon the application of the braking power to the brake shoes in such a manner 40 as to automatically make the shoes tend to set themselves against the rails, and thereby assist in the holding action, which is commenced or instituted, in the preferred form of my invention, wholly by air pressure and toggles, so that the greater the 45 load upon the car, the greater will be the grip of the brake-shoes upon the guide rails.

The present invention also includes a special construction of power levers or toggle levers, which secure certain functions later pointed out. With these and other objects in view, my invention consists in the features of construction and combination as 50 hereinafter set forth and claimed.

In the drawings: Figure 1 is an end elevation of an elevator brake embodying the principles of my invention, the guide rail of the elevator shaft being shown in section. Fig. 2 is a horizontal sectional view of the same on the line II-II of Fig. 1. Fig. 3 60 is a partly sectional view showing the brake shoes in their open or non-engaging position on the guide rail. Fig. 4 is a similar view showing the brake-shoes applied or clamped upon the guide rails. Fig. 5 is a 65 detail side elevation of one of the shoes.

Referring to the drawings in which like parts are designated by the same reference sign, 1 designates a frame constituting the body or support of the brake. 70

2 is a power cylinder which I preferably form integral with the supporting frame 1.

3 designates a piston moving in the power cylinder 2 and having a piston-rod 4 provided with a cross-head 5 outside the cylinder-head 6. This cylinder-head guides the stroke of the piston-rod 4. The piston 3 is normally pressed to its innermost position by means of the spiral spring 8 mounted within the cylinder 2. 9-9 designate 80 equalizing links which are pivoted by pins 10 to the cross-head 5. Each of the links 9 are in duplicate, pivoted on opposite sides of the cross-head 5. At their outer ends these links have pivoted thereto by the pins 11 the diverging arms 12. At the point of connection of the links 9 and arms 12, the latter are reduced in thickness to correspond with the thickness of the cross-head 5, and the abutting faces 15 of said arms have an 90

arcuate outline, the arcs being of such radii that the abutting faces impinge against each other at all times when the piston-rod 4 is pushed toward its outermost position in a manner to be hereinafter described. The 95 outer ends of the two arms 12 are bifurcated and have pivoted therein the power levers 13 by means of the pins 14. It is evident that the diverging arms 12 act together to form a toggle joint between the power arms 100 13 and the force and manner of the toggle action is dependent on the curvature and form of the arcuate faces 15. By properly shaping these faces 15 it is possible to make the power factor of the toggle joint increase 105 in a definite and regular manner. Besides this, the foregoing structure is a specially advantageous one in that no minor irregu-

larities in the fitting of the parts or in the alignment of the guide-rails or like fixed parts in the elevator shaft can have any effect on the working of the brake, since the links 9 are free to swing from side to side and always work as above described whether they are inclined or in parallelism with the line of movement of the piston. It is also to be observed that the links 9 and arms 12 are prevented from bending or buckling in about their connecting pivots 11 into positions directly opposite the operative or normal positions shown, by the engagement of the power arms 13 with the shoulders 12' of the bifurcated portions of levers 12.

20 denotes brake-shoes, of which two are provided to grasp a fixed part or member of the elevator run-way. This fixed part, designated A, is preferably the guide-rail, 20 but may be a brake rail, cable or the like. The shoes are operated by the power arms 13, and the essential principle or characteristic of the shoes 20 is that they tend to automatically set or wedge themselves 25 against the guide rail or fixed member A whenever the power is applied thereon from the power arms. As will later appear, I may employ different types of power arms and different types of brake-shoes embodying the principles of the present invention. 30 With the form of power arms 13, as already described, I prefer to employ pivoted brake shoes adapted to swing about fixed pivot studs 22 which project from the frame or body 1. These brake-shoes are not pivoted to the studs 22 in the manner of an ordinary pivot or bearing support, but have inclined slots 23 having a widthwise diameter equal to the diameter of the pivot studs 22 and a 40 lengthwise diameter considerably greater than the diameter of said pivot studs thereby permitting a certain independent movement of the shoes on the pivot studs in the direction of the inclination of these slots. 45 The inclination of the slots is such as to cause the shoes 20 to approach one another under the influence of any upward pressure exerted thereon. Each of the shoes 20 has a pivot connection 24 with what may be termed shoe links 27. The shoe links 27 are pivoted at 26 to the forward extremities of the power arms 13. In accordance with my present invention, the shoe links 27 are not directly pivoted to the shoes 20 by their pins 24, but move in inclined slots or guideways 25 within said shoes, the inclination of these slots being opposite to that of the slots 23. The shoes 20 may be lined with any suitable friction lining 28, for which I prefer camel's hair fabric in practice.

50 The use and operation of this form of my invention is as follows: Assuming that an application of the brakes becomes necessary with the car ascending or descending, air pressure is supplied to the cylinder 2, driv-

ing the piston 3 outward and expanding the diverging arms 12 in such a way as to separate the power arms 13 and impel the shoe links 27 toward one another. These shoe links have an engagement with the brake 70 shoes 20 through their pivot pins 24, the latter occupying the relation of Fig. 3 at this time. The application of the air or other fluid pressure is accompanied by the quick inward movement of the brake-shoes 75 toward the member A, and during this movement the pins 24 travel toward the lower ends of the slots 25. This travel of the pins 24 in the inclined slots 25 evidently exerts a tendency to lift the brake-shoes 20, and this tendency is strongly aided by the engagement of the lower portions of the friction linings with the sides of the fixed member when the car is descending, owing to the weight and movement of the car, which 85 urges the shoes upward relatively to the car and in turn drives the upper ends of said shoes in toward the rail with tremendous force, the shoes moving inwardly with respect to studs 22 and the oblique slots 23 90 co-acting with said studs to exert a powerful wedge action. The relative upward travel of the shoes allows each pin 24 to approach the inner end of its respective slot 25, so that the arms 12 are allowed to assume a 95 position approaching alignment, resulting in a maximum toggle effect at this point in the apparatus which in turn increases the pressure upon the lower ends of the shoes and thereby still more strongly wedges the 100 upper ends of the shoes into engagement with the rail. Furthermore owing to the fact that the shoes are pivotally or oscillatably mounted upon the studs 22 there is some tendency for the lower ends of the 105 shoes to rotate inwardly toward the rail, increasing the gripping action of the lower portions of the shoes and thereby further wedging the upper portions against the pivot studs. Thus the action of the device 110 when descending is retroactively cumulative and the braking effect is enormous. This is most advantageous since the greatest braking effect is needed when a falling car is to be checked or stopped. When the 115 brake is applied to an ascending car, or when applied to lock a stationary car, it operates less powerfully since the wedging action is to some extent opposed by the frictional engagement of the shoes and the fixed 120 member or rail and the cumulative effect just described is absent. The brake, however, is nevertheless effective in this case, since the force to be overcome is very materially less than in the case of a descending 125 or falling car, and the rocking toggle formed by the eccentric toggle arms 12 is sufficiently powerful to force the pins 24 inward in the manner above described and to thereby press the shoes upward attaining 130

a proper wedge action. In either case whether the car be ascending or descending, it is quickly brought to rest.

It will be observed that the degree of the 5 braking action when braking a falling car is somewhat dependent upon the speed and momentum of the car, being more efficient as the momentum increases, as is desirable.

Another advantage of the pin and slot 10 connection 22, 23, between the shoes and the casing 1, is that it permits a lateral adjustment of the shoes when their faces are parallel to the faces of the fixed rail with which they contact; or in other words, after a shoe 15 has been brought into contact with the fixed rail so that practically its entire surface is in contact therewith, the shoe may adjust itself bodily with respect to the power arm to compensate for any irregularity in the 20 width of the fixed rail or compensate for any wear occurring upon the shoes. In the construction shown in my former patents the shoes are pivoted upon the casing 1, but have no automatic lateral bodily movement 25 with respect thereto, and it was found such a construction would not permit the entire surface of the shoe to rest against the rail when in contact therewith, especially if there was a slight difference in the thickness of 30 the rail at various points along the elevator shaft, or if the shoe became worn, in which instance only a portion of the surface of the shoe would be in contact with the fixed rail. By mounting the shoe for a lateral, as 35 well as a swinging movement upon its pivot, this objection is obviated, since after the shoe has been forced into intimate contact with the fixed rail so that its entire surface is in contact and parallel therewith, the shoe 40 may still have a slight bodily lateral movement sufficient to permit it to adjust itself and compensate for any irregularities due to the variations in the thickness of the rail or in the wear upon the shoe.

45 Having described my invention, I claim:—
1. In an elevator braking appliance, a fixed part, a pair of slidably pivoted shoes adapted to grip said fixed part, and means for initially moving said shoes into frictional engagement with said part, said means comprising members having pin and inclined guideway engagements with said shoes, said shoes moving laterally with respect to said members, when the latter are 50 operated.

55 2. In an elevator braking appliance, a fixed part, a pair of shoes adapted to grip said fixed part, means for impelling said shoes into engagement with said part, fixed studs having an inclined slot connection with said shoes and links joined to said means and also having an inclined slot connection with said shoes.

60 3. In an elevator braking appliance, a fixed part, a pair of power arms, a pair of

fixed studs, shoes having slots converging upwardly toward the fixed part and receiving said studs, and links joining said shoes and said power arms, said links having a 65 slideable connection with said shoes.

70 4. In an elevator braking appliance, a fixed rail, a member carried by the car, a pair of brake shoes adapted to engage the opposite faces of said rail, power arms mounted on said member one connected to 75 each of said shoes and exerting when actuated, a pressure on said shoes substantially at right angles to the rail, means for actuating said power arms, said shoes also having an inclined slot and stud connection with 80 said member permitting said shoes to adjust themselves laterally with respect to the rail independently of the power arms and of each other and causing the shoes to wedge themselves between the member and the 85 fixed rail when the brake shoes are applied.

5. In an elevator braking appliance, a fixed rail, a member carried by the car, a pair of brake shoes adapted to engage opposite faces of said rail for a substantial portion 90 of their length and loosely pivoted on said member to have a lateral movement with respect thereto and to be wedged between said fixed rail and member when the shoes are pressed against the rail, a pair of 95 power arms and connections between said power arms and shoes for pressing said shoes against said rail.

6. In an elevator braking appliance, a fixed rail, a member carried by the car, a 100 pair of brake shoes adapted to engage opposite faces of said rail for a substantial portion of their length, each shoe having a loose connection with said member comprising an inclined wall and a relatively fixed part 105 co-operating therewith, a pair of power arms one connected to each of said shoes for pressing said shoes against said rail and exerting a pressure thereon substantially at right angles to said fixed rail, and means for actuating said power arms.

7. In an elevator braking appliance, a fixed rail, a member carried by the car, a pair of shoes adapted to engage opposite faces of said rail for a substantial portion 115 of their length, a pair of fixed studs on said member, said shoes having inclined slots fitting over said studs, said slots of the pair of shoes converging upwardly, a pair of power arms, means connecting said shoes to 120 said power arms for exerting a pressure upon said shoes substantially at right angles to the fixed rail when actuated and means for actuating said power arms.

8. In an elevator braking appliance, a 125 fixed rail, a member carried by the car, a pair of shoes adapted to engage opposite faces of said rail for a substantial portion of their length, loose connections between each of said shoes and said member compris- 130

ing an inclined wall and a fixed part co-operating therewith, the inclined walls of said connections converging upwardly, power arms, links connecting said arms to said shoes for exerting a pressure upon said shoes substantially at right angles to said rail, and means for actuating said arms.

In witness whereof, I subscribe my signature, in the presence of two witnesses.

ALFRED H. MEECH.

Copies of this patent may be obtained for five cents each, by addressing the "Commissioner of Patents, Washington, D. C."

It is hereby certified that the State of incorporation of the assignee in Letters Patent No. 1,206,350, granted November 28, 1916, upon the application of Alfred H. Meech, of Chatham, New York, for an improvement in "Elevator-Brakes," was erroneously written and printed as "Missouri," whereas said State should have been written and printed *Maine*, as shown by the records of assignments in this office; and that the said Letters Patent should be read with this correction therein that the same may conform to the record of the case in the Patent Office.

Signed and sealed this 26th day of December, A. D., 1916.

[SEAL.]

R. F. WHITEHEAD,
Acting Commissioner of Patents.
